US00D962082S

(12) United States Design Patent (10) Patent No.: US D962,082 S
(45) Date of Patent: * Aug. 30, 2022

(54) PACKAGE

(71) Applicant: Kraft Foods Group Brands LLC,
Chicago, IL (US)

(72) Inventors: Jonathan Wiese, Chicago, IL (US);
Charles Phillips, Hartsville, SC (US);
Ryan Boudreaux, Fairfield, CT (US);
Luis Ramiro Gutierrez Montenegro,
Fairfield, CT (US); Michelle Cozo Pollard, Chicago, IL (US)

(73) Assignee: Kraft Foods Group Brands LLC,
Chicago, IL (US)

() Term: 15 Years

(21) Appl. No.: 29/711,164

(22) Filed: Oct. 29, 2019

(51) LOC (13) Cl. 09-03

(52) U.S. Cl. D9/756
USPC ....

(57) CLAIM

The ornamental design for a package, as shown and described.

DESCRIPTION

FIG. 1 is a front perspective view showing a first embodiment of our new design of a package;

FIG. 2 is a top plan view thereof;

FIG. 3 is a front elevation view thereof, the rear elevation view being identical thereto;

FIG. 4 is a side elevation view thereof, the other side elevation view being identical thereto;

FIG. 5 is a bottom plan view thereof;

FIG. 6 is a front perspective view showing a second embodiment of our new design of a package;

FIG. 7 is a top plan view thereof;

FIG. 8 is a front elevation view thereof, the rear elevation view being identical thereto;

FIG. 9 is a side elevation view thereof, the other side elevation view being identical thereto; and,

FIG. 10 is a bottom plan view thereof.

The broken lines shown illustrate portions of the package and form no part of the claimed design.

1 Claim, 6 Drawing Sheets
